UNITED STATES PATENT OFFICE.

ARTHUR GORDON WHEELER, OF MONTGOMERY, ALABAMA.

MOP.

Application filed March 24, 1926. Serial No. 97,056.

This invention relates to improvements in mops of the kind customarily used for dusting, polishing and similar functions in house cleaning, and one of the foremost objects of the invention is to provide such construction as will permit of easy reversal of the mop head even while in use so that advantage may be taken of both sides.

Other objects and advantages appear in the following specification, reference being had to the accompanying drawing in which—

Figure 1 is a perspective view of the improved mop.

Figure 2 is a plan view of the wire head frame and a portion of the handle, the mop head being shown in dotted lines.

Figure 3 is a detail section taken substantially on the line 3—3 of Figure 2, illustrating the typical manner of forming an opening in the twisted wire frame.

Figure 4 is a detail sectional view taken substantially on the line 4—4 of Figure 1.

Figure 5 is a detail cross section on the line 5—5 of Figure 1.

Figure 6 is a detail perspective view of the slidable ring.

Figures 7, 8 and 9 are detail views illustrating slight modifications in the form of the mop head frame.

In carrying out the invention provision is made of a handle 1 of suitable length and material, which is bored transversely at 2 near one extremity to receive the closed end 3 of a U-shaped clamp and connector 4. The ends of the connector are bent outwardly to produce pintles 5 to extend in opposite directions but in coaxial relationship.

The U-clamp and connector 4 is bent into shape from a piece of sufficiently heavy wire having sufficient resiliency to permit of flexing the connector by squeezing the free extremities together, thereby releasing the mop head as presently appears. The U-clamp is held in fixed position upon the handle 1 by means of a ring or band 6. This band is formed in the manner clearly shown in Figures 5 and 6, there being a portion encircling the handle 1 and bent portions 7 and 8 passing around the members of the U-clamp.

In constructing the mop head the strands of worsted 9 or other material customarily employed are inserted between the wire strands 10 and 11 of which the frame 12 (Fig. 3) is made, and inasmuch as the wire

strands are twisted together very tightly, it follows that the worsted strands are firmly yet simply clamped in position. In bending the twisted wire into shape, the end portions thereof are looped as shown and secured to the intermediate portion of the frame.

In twisting the strands 10 and 11 of the wire frame together, provision must be made for the insertion of the pintles 5 as well as the rivet 13 which secures the extremities of the frame wire to the back as shown in Figure 2. The wire is simply twisted around a sufficiently large plug of wood, metal or the like to produce a slightly enlarged space resulting in an opening or loop as at 14 in Figure 3. Withdrawal of the plug leaves the opening and the opening is subsequently used for the insertion of one of the pintles 5 as stated. Similar steps are taken for the formation of openings at 15, 16 and 17 (Fig. 4) for the insertion of the rivet 13.

The specific shape of the twisted wire head frame 12 is subject to considerable variation as can be seen in Figures 2, 7, 8 and 9, but there is one common characteristic of all shapes of the head frame and that is the passage-way 18 formed at one side. In Figure 2 the head frame is of substantially rectangular shape, the various corners being fully rounded so that there may be no possible sharp projection. The wire frame is bent into shape from a single strand of twisted wire and the frame is so formed as to leave a passage way 18 into which the extremity of the U-clamp can enter to make pivotal connection at the confronting openings 14.

The passage-way 18 occurs at the side opposite to the straight and relatively long side to which the extremities of the wire are applied and riveted as shown. The riveting occurs at the base of the passage-way, and both heads of the rivet are easily accessible for the necessary operation of upsetting. In Figure 7 the head frame may be described as consisting of a double loop or a substantial 8, and although the passage-way 18 is not so pronounced as in Figure 2, it is there, nevertheless, and serves the purpose of receiving the pintles 5 of the clamp 4 as before.

In Figure 8 the headframe is of substantially triangular shape, the formation being such as to produce the passage-way 18 as before. In Figure 9 the frame is round,

one side being bent in to produce the passage-way 18. Many different shapes of headframes can be produced on the same principle.

5 The operation is readily understood. The specific formation of the twisted wire head frame in reference to which the provision of the passage-way 18 is emphasized above, permits of a very important function in the 10 use of the mop. The engagement of the pintles 5 with those portions of the frame paralleling the passage-way 18 constitute the pivotal connection of the mop head upon the extremity of the handle. It is at 15 this pivotal connection that the mop head can swing through a very great arc so that either one or the other side may be presented for cleaning purposes.

Consider Figure 4. One side of the mop 20 head is in position for cleaning or polishing a floor or other surface. Assume that it is desired to turn the mop head over. The passage-way 18 permits turning of the head in the directions of the arrows *a* and *b* so 25 that the side which is now down will then be up, and vice versa. This turning of the mop head requires no adjustment whatever: the mop is simply lifted from the floor, whereupon a swing in the proper direction will turn the head over as stated.

30 The foregoing reversible feature of the mop head gives a 100% additional use of the mop, and is one of the objects of the invention. Mops of this character usually embody such construction in the wire frame that only one side can be used, and they are therefore non-reversible. All of the components of the twisted wire frame are in a single plane, and it is therefore possible to 35 wash the mop head (having first removed it from the handle by squeezing the free extremities of the connector 4 together) and run it through a wringer. Ordinarily mops 40

cannot be wrung out but must be hung up to dry.

It is observed that the handle 1 and U-clamp 4 can be lowered until they occupy the same plane as the wire frame 12. To say that the entire mop can be spread out flat may be more expressive than accurate, but it conveys the idea that the mop handle can be lowered until it touches the floor, thereby permitting the mop head to be pushed under very low pieces of furniture. In view of the fact that there are no projecting parts it follows that the danger of marring furniture is obviated entirely. Upon lifting the mop handle the head swings to such position that when the mop handle is again let down the head will contact the floor in proper position for work.

While the construction and arrangement of the improved mop is that of a generally preferred form, obviously such modifications and changes may be made as do not depart 55 from the spirit of the invention and the scope of the claims.

I claim:

1. A twisted wire mop carrying frame having its end portions looped and secured to the intermediate portion of the frame providing a recess having adjacent sides and opposed openings formed in the adjacent sides, and a handle pivotally mounted in the openings.

2. A mop comprising a handle, an element carried at one extremity of the handle having pintles constituting suitable mounting means, and a twisted wire mop carrying frame having a pair of substantially parallel portions attached to an intermediate portion of the frame, pivot openings formed in said substantially parallel portions to receive said pintles, said openings being located in confronting positions.

A. GORDON WHEELER.
